(57) **CLAIM**

The ornamental design for a utility lighter, as shown and described.

DESCRIPTION

FIG. 1 is a perspective view from above of a design for a utility lighter, showing my new design;

FIG. 2 is an isometric view of one side of the design for the utility lighter;

FIG. 3 is an isometric view of the other side of the design for the utility lighter;

FIG. 4 is a top plan view of the utility lighter;

FIG. 5 is a bottom plan view of the utility lighter;

FIG. 6 is an isometric view of the front of the utility lighter; and,

FIG. 7 is an isometric view of the back of the utility lighter.
